UNITED STATES PATENT OFFICE.

CHESTER WM. CRUMRINE, OF ROCHESTER, NEW YORK, ASSIGNEE, BY MESNE ASSIGNMENTS, TO NORTH EAST APPLIANCES, INC., OF ROCHESTER, NEW YORK, A CORPORATION OF NEW YORK.

POWER MECHANISM.

Application filed September 24, 1924, Serial No. 739,702. Renewed February 26, 1927.

This invention relates to power mechanism such as is used for actuating a typewriter or similar machine. In such mechanism it has been proposed to use a constantly driven rotary member or roller, and to connect each type-bar with a cam, or other device, adapted to co-operate with the power roller when released by one of the keys of the machine.

10 The present invention relates particularly to the connecting devices interposed between the type-bar, or other element which is to be actuated, and the cam-unit or equivalent part which actuates it. The object of the invention is to produce a simple and readily accessible device by which the connections in question may be accurately adjusted and by which the adjustment will be automatically maintained. To the foregoing ends the 20 invention consists in the structure herein-after described, as it is defined in the annexed claim.

In the accompanying drawings Fig. 1 is a side-elevation of power mechanism embodying the present invention. Fig. 2 is an enlarged side-elevation showing the adjustable connecting devices in section. Figs. 3 and 4 are bottom views of the parts shown in Fig. 2, in different positions.

30 The invention is illustrated as used in connection with power mechanism in which a cam 5 is journaled in a lever which is mounted on a stationary pivot 6. The cam co-operates with a power-driven roller 7, 35 the cam-lever is connected with the type-mechanism or any other part of the machine which is to be actuated, by means of a pull-rod 8. The cam-mechanism is thrown into operation by means of one of the key-levers 40 9 of the machine.

The operation of the cam is controlled by a stop-lever 10 articulated with the key-lever as shown in Fig. 1. Since the details of this cam-mechanism and of its mode of operation are not involved in the present invention, they need not be further described herein, but it will be understood that when the key-lever is depressed the cam is permitted to engage the power-roller and thus to swing the cam-lever in a direction to pull on the pull-rod 8.

The structure embodying the present in-

vention is shown particularly in Figs. 2, 3, and 4. The horizontal part of the cam-lever comprises two parallel sheet-metal arms 11. 55 These are connected rigidly at the proper distance by means of a U-shaped sheet-metal member, comprising a horizontal part 12 and two depending end-portions 13. The end-portions are provided with laterally projecting lugs 14, which are received in slots in the arms 11 and are riveted over so as to fasten the arms rigidly together. 60

The arms 11 are perforated, near their ends, to receive a pivot 15 which has reduced 65 ends 16 loosely engaging the perforations. The pivot 15 is bored vertically to receive a shank 17, which is fixed in the lower end of a sleeve 18. The sleeve is screw-threaded to engage the screw-threaded lower end of 70 the pull-rod 8. At the lower end of the shank 17 is a polygonal head 19 provided with a slot to receive a screw-driver.

In the normal position of the parts, as shown in Fig. 3, the arms 11 rest against two 75 flat sides of the head 19 and prevent the head and the sleeve 18 from turning accidentally. The pivot 15 is free to rock with respect to the arms 11, and thus affords a pivotal connection for the lower-end of the pull-rod. 80 If it be desired to adjust the normal position of the arms up or down, to correct the clearance between the cam 5 and the roller 7, this may be done by inserting a screw-driver in the slot in the head 19 and turning 85 this head in one direction or another, thus causing the sleeve 18 to screw up or down on the pull-rod. When the head is so turned its angles force the arms 11 slightly apart, as shown in Fig. 4, but owing to their resiliency, they return again so as to press against the flat sides of the head in its finally adjusted position. 90

Among other advantages of this adjustable connection is the fact that it is accessible from beneath, which is the most convenient direction of access to mechanism of the kind in question, and the further fact that the use of the two arms 11 involves no increase in the cost of the mechanism, since 100 the cam-lever must in any case be made of two parallel members of sheet-metal.

The invention claimed is:
In a typewriter or the like, the combina-

tion, with a lever comprising two resilient arms disposed side-by-side, and power-means for actuating the lever, of a pivot-member journaled at its ends, in and between said arms, and transversely perforated; a shank rotatable in the perforation in the pivot-member and provided with a head having

flattened surfaces normally engaged by the inner surfaces of the arms; and a connecting-member comprising two screw-threaded parts relatively adjustable by relative rotation, one of said parts being attached to said shank.

CHESTER Wm. CRUMRINE.
